UNITED STATES PATENT OFFICE.

JOSEPH BERGER, JR., OF UTICA, NEW YORK, ASSIGNOR TO UNION SPECIAL MACHINE COMPANY, OF CHICAGO, ILLINOIS, A CORPORATION OF ILLINOIS.

THROAT-PLATE FOR SEWING-MACHINES.

1,305,051.

Specification of Letters Patent. Patented May 27, 1919.

Application filed July 20, 1915. Serial No. 40,891.

To all whom it may concern:

Be it known that I, JOSEPH BERGER, Jr., a citizen of the United States, residing at Utica, in the county of Oneida, State of New York, have invented certain new and useful Improvements in Throat-Plates for Sewing-Machines, of which the following is a description, reference being had to the accompanying drawing and to the figures of reference marked thereon.

The invention relates to new and useful improvements in throat plates for sewing machines, and more particularly to a throat plate for a sewing machine having two sets of stitch forming mechanisms, one of which is substantially in rear of the other.

An object of the invention is to provide a throat plate with two stitch tongues, one of which is in rear of the other, the rear stitch tongue being narrower than the stitch tongue in front thereof, so that a cross stitching mechanism coöperating with the rear stitch tongue will tie down the cross threads of a cross stitching mechanism co-
operating with the front stitch tongue.

A further object of the invention is to provide a throat plate of the above character, wherein the rear stitch tongue is formed integral with the front stitch tongue, so that the cross threads of the front stitching mechanism will slide off the rear end of the rear stitch tongue.

A still further object of the invention is to provide a throat plate which coöperates with a feed dog, wherein one of the elements is formed with a stitch tongue adapted to coöperate with widely spaced needles, and one of the elements is also provided with a relatively narrow stitch tongue located in rear of the front stitch tongue and adapted to coöperate with relatively closely spaced needles.

These and other objects will in part be obvious and will in part be hereinafter more fully disclosed.

In the drawings which show by way of illustration one embodiment of the invention—

Figure 1 is a plan view of the forward end of a cylindrical work support having my improved throat plate applied thereto;

Fig. 2 is a similar view, showing in plan the presser foot which coöperates with the throat plate;

Fig. 3 is a top plan view of the throat plate detached from the machine;

Fig. 4 is a longitudinal sectional view through the throat plate, showing the needles, the loopers, the feed dog and the presser foot;

Fig. 5 is a perspective view of the throat plate and feed dog, showing a slightly modified form of the invention;

Fig. 6 is a transverse sectional view through the feed dog, showing the manner of supporting the stitch tongue thereon;

Fig. 7 is a plan view of the throat plate having another slightly modified form of the invention;

Fig. 8 is a plan view of a throat plate having a still further modified form of the invention;

Fig. 9 is a perspective view of the feed dog, showing one of the stitch tongues mounted thereon;

Fig. 10 is a perspective view of a throat plate adapted to coöperate with the feed dog shown in Fig. 9; and

Fig. 11 is a plan view of a throat plate showing a still further modified form of the invention.

In Fig. 1 of the drawings, I have shown the end of a cylindrical work support 1, on which is mounted a throat plate 2, having my invention embodied therein. Said throat plate is secured to the work support by suitable screws 3—3. The throat plate is provided with feed slots 4, into which extends the feed dog 5. Said throat plate is also provided with an opening 6, into which extend the stitch tongues 7 and 8. The stitch tongue 7 is supported by the throat plate and projects rearwardly into the opening 6. Said stitch tongue is substantially the width of the opening leaving only slots of sufficient space at each side of the tongue for the cross threads to slide along the stitch tongue. The forward needles enter the enlarged openings 9—9 at the front ends of the slots along the sides of the stitch tongue 7. The rear stitch tongue 8, which is formed integral with the stitch tongue 7,

100

as shown in Figs. 1, 3, 4, 5 and 7 is a relatively narrower stitch tongue, having its side walls parallel. The underfaces of the stitch tongues are tapered as at 10 and 11, 5 respectively, the tapered surfaces merging for a purpose which will hereinafter appear.

Coöperating with the throat plate is a presser foot 12, which is provided with a slot 13, through which the needles 14 and 10 15 enter, see Fig. 2. These needles pass through the openings 9—9 alongside of the stitch tongue 7. Said presser foot is also provided with an opening 16 through which the needles 17 and 18 pass. These needles 15 are adapted to pass alongside of the stitch tongue 8 adjacent the end of the stitch tongue 7. Coöperating with the needles 14 and 15, beneath the work support, is a looper 19, while coöperating with the needles 17 20 and 18, beneath the work support, is a looper 20. Inasmuch as there is a single looper coöperating with each pair of needles, there will be a cross thread formed joining each set of needle loops beneath the material and 25 these cross threads are respectively laid across the stitch tongues 7 and 8. Inasmuch as the needles 17 and 18 are spaced closer together than the needles 14 and 15 and are located directly in rear of the same, the needle loops and the cross threads of the rear set of needles will tie down or overlie the cross threads joining the needle loops of the needles 14 and 15. The cross threads connected with the needle loops of the needles 30 14 and 15 slide off from the end of the stitch tongue 7 on to the stitch tongue 8 and then off from the stitch tongue 8, the merging of the tapered undersurfaces 10 and 11 of these tongues assisting in this action. The 35 longitudinal center line of the stitch tongue 8 coincides with the longitudinal center line of the stitch tongue 7, as shown in the drawings.

In Figs. 5 and 6 of the drawings, I have 40 shown a modified form of the invention. In this form of the invention, the stitch tongues are carried by the feed dog instead of by the throat plate. The throat plate 2 has the stitch tongue cut out of the same forming 45 an enlarged opening 21. The feed dog has a portion of its feed teeth cut away and a plate 22 is secured to the feed dog by a screw 23. Said plate has a groove in its underface adapted to engage the rib 24 on 50 the feed dog, whereby a single screw holds the plate firmly upon the feed dog. Said plate 22 at its forward end is provided with spaced parallel slots 25 and 26, forming a stitch tongue 7^a. These slots at their rear 55 ends respectively receive the needles 14 and 15. The stitch tongue 7^a is similar in construction to the stitch tongue 7, above described, except it is carried on the plate 22 mounted on the feed dog instead of being 60 carried by the throat plate. The same is

true of the stitch tongue 8^a. It will be noted that the stitch tongues 7^a and 8^a move back and forth with the feed. These stitch tongues, however, operate precisely in the same way, relative to the pairs of needles, as 70 above described.

In Fig. 7, I have shown a modified form of the rear stitch tongue. The front stitch tongue 7 is precisely the same in construction as the stitch tongue described in connection with Figs. 1 to 3. The stitch tongue 8^b is wider than the stitch tongue 8, but of less width than the tongue 7, and recesses 27 and 28 are provided at the juncture of said tongues for the needles 17 and 18, respectively. In this form of the stitch tongue, the stitches formed by the thread from needles 17 and 18 and the connecting looper thread are held in looser condition, so that the resulting seam is more elastic. 80

In Fig. 8 of the drawings, I have shown a further modified form of the invention. The throat plate 2 is similar in construction to the throat plate shown in Fig. 1, except as to the manner of supporting the stitch 90 tongues. Instead of having one opening 6 in the throat plate, there are two separate openings 29 and 30. The stitch tongue 7^c projects into the opening 29 and is spaced from the side and end walls thereof, so as to permit the cross threads to slide off from the stitch tongue. The stitch tongue 8^c is carried by the throat plate and projects into the opening 30 and is spaced from the side and end walls thereof. This stitch tongue 95 is of considerably less width than the stitch tongue 7^c, and the needles coöperating with these stitch tongues 7^c and 8^c are spaced, as shown in Fig. 2. Each stitch tongue is separately supported and one is in rear of the other, so that the cross threads laid across the first stitch tongue may be released on to the material being stitched before said cross threads are stitched down by the rear 100 pair of needles.

From the above, it will be noted that the throat plate is formed with a cross bar which separates the needle openings and this cross bar supports the stitch tongue 8^c. The cross bar not only supports the stitch tongue but insures that the looper thread connecting the needles coöperating with the first stitch tongue shall be brought up on to the throat plate and over the tongue 8^c. 110

In Figs. 9 and 10, I have shown a further modified form of the invention. In this form of the invention, the stitch tongue 8^d is carried by the feed dog. The feed dog is indicated at 5. The plate 31 is secured to this feed dog and carries this stitch tongue 8^d. Said plate is formed with slots 32 and 33 for the needles 14 and 15, respectively, and the stitch tongue is located between these slots. In this form of the invention, the stitch tongue 8^d is similar to that de- 125 130

scribed in connection with Fig. 8. The plate 31 is secured to the feed dog 5 in the manner shown in Fig. 6.

In Fig. 11, I have shown a still further modified form of the invention. The throat plate 2 is formed with two openings 29 and 30 and the stitch tongues 7^e and 8^e are located in these respective openings. The stitch tongue 7^e is supported at the side of the opening and extends laterally and then rearwardly between the needles 14 and 15. The stitch tongue 8^e is supported at the side of the opening 30 and extends laterally and then rearwardly between the needles 17 and 18. The rear stitch tongue is narrower than the forward stitch tongue and operates in the manner above described.

From the above description, it will be apparent that I have provided two stitch tongues which are adapted to coöperate with two sets of stitching mechanisms, one in rear of the other, and these stitch tongues are of such construction that the rear stitch forming mechanism operates independently of the front stitch forming mechanism to form cross threads which join the needle loops, which in turn tie down the cross threads of the front stitch forming mechanism and the resulting seam of both stitch forming mechanisms is an elastic seam—that is, the joining cross threads are laid over the stitch tongues and held thereon while the stitches are set, so that when said cross threads slide off the stitch tongues the seam will be more or less elastic. It is also apparent that the rear pair of needles 17 and 18 are disposed in rear of the front pair of needles 14 and 15, and that each needle of the rear pair of needles is disposed in plane extending between the needles of the front pair of needles.

Having thus described my invention, what I claim as new and desire to secure by Letters Patent, is:

1. A throat plate for sewing machines having feed slots and two stitch tongues, one tongue being disposed in rear of the other, said rear stitch tongue being relatively narrower than the stitch tongue in front thereof, whereby the cross threads of a stitching mechanism coöoperating with the forward stitch tongue will subsequently be tied down by the cross threads of a stitching mechanism coöoperating with the rear stitch tongue.

2. A throat plate for sewing machines having feed slots and two stitch tongues, one tongue being disposed in rear of the other, said rear stitch tongue being relatively narrower than the stitch tongue in front thereof, the longitudinal center line of the rear stitch tongue coinciding with the longitudinal center line of the front stitch tongue.

3. A throat plate for sewing machines 65 having feed slots and two stitch tongues, one in rear of the other, said rear stitch tongue being carried by the forward stitch tongue.

4. A throat plate for sewing machines 70 having feed slots and two stitch tongues, one in rear of the other, said rear stitch tongue being formed integral with and carried by the forward stitch tongue, said rear stitch tongue being relatively narrower than 75 the stitch tongue in front thereof, whereby the cross threads laid over the forward stitch tongue will be tied down by the stitching mechanism coöoperating with the rear stitch tongue.

5. A throat plate for sewing machines having feed slots and an opening therein, a stitch tongue carried by the throat plate and projecting rearwardly into said opening, a second stitch tongue narrower than 85 the first stitch tongue and carried thereby and projecting rearwardly into said opening.

6. The combination of a throat plate and a feed dog, stitch tongues carried by one of said elements, one of said stitch tongues 90 being in rear of the other and carried thereby, and said stitch tongues being adapted to coöperate respectively with pairs of spaced needles, and the needles coöperating with the forward stitch tongue being spaced 95 a greater distance than the needles coöperating with the rear stitch tongue.

7. The combination of a throat plate, a feed dog, a stitch tongue carried by one of said elements and projecting rearwardly 100 in the line of feed, a second stitch tongue carried by the first named stitch tongue, said second stitch tongue being relatively narrower than the first named stitch tongue.

8. The combination with a throat plate 105 and a feed dog, said throat plate having needle openings for two pairs of needles, one of which is located in rear of the other, the rear pair being spaced closer than the front pair, one of said elements having a 110 stitch tongue extending between the front pair of needles only and one of said elements having a stitch tongue extending between the rear pair of needles, said stitch tongue for the rear pair of needles having 115 its supporting means extending between the front pair of needles, said stitch tongues being proportioned so as to correspond with the spacing of the respective pair of needles with which it coöperates.

9. A plate having needle openings therein, a plurality of stitch tongues carried by said plate, one of said stitch tongues being disposed so as to shed the threads formed around the same on to the other 125 stitch tongue.

10. A plate having needle openings therein, a plurality of stitch tongues carried by

said plate, one of said stitch tongues being disposed so as to shed the threads formed around the same on to the other stitch tongue, the forward stitch tongue being of 5 greater width than the rear stitch tongue.

11. A plate having needle openings therein, a plurality of stitch tongues carried by said plate, one of said stitch tongues being disposed so as to shed the threads formed 10 around the same on to the other stitch tongue, the forward stitch tongue being of greater width than the rear stitch tongue, both of said stitch tongues being tapered 15 toward the free end to facilitate the shedding of the threads.

12. The combination of two pairs of needles, one in advance of the other, of a stitch tongue for each pair of needles, said stitch tongues being so disposed that the threads

laid around the forward stitch tongue are 20 shed on to the rear stitch tongue.

13. The combination of two pairs of needles, one in advance of the other, of a stitch tongue for each pair of needles, said stitch tongue being so disposed that the threads 25 laid around the forward stitch tongue are shed on to the rear stitch tongue, said forward stitch tongue being of greater width than the rear stitch tongue, and both of said stitch tongues being tapered toward the free 30 end of said stitch tongues to facilitate the shedding of the threads therefrom.

In testimony whereof, I affix my signature in the presence of two witnesses.

JOSEPH BERGER, JR.
